(57) **ABSTRACT**

A collapsible wind-resistant umbrella including an elongated main support pole and an umbrella top. The umbrella top includes a tubular secondary pole slidably translatable over the main support pole, a hub connected at an upper end thereof to the secondary pole and supportively engaged against a support member on the main support pole whereby the secondary pole and hub are supported on the upright main support pole. A plurality of vanes, each being wider at the outer end thereof, are pivotally connected in evenly spaced relation at a central or inner end thereof to and around substantially the entire hub periphery. A vane carrier is mounted for sliding translation over the secondary pole and a plurality of rigid or semi-rigid vane support rods are pivotally connected at one end thereof in evenly spaced relation to and around substantially the entire said vane carrier periphery. The end of each said vane support rod is pivotally connected to a mid point of one longitudinal edge of each corresponding vane. An elongated endless non-elastic cord extends circumferentially around and is connected to each vane adjacent its outer or distal end. The other edge of each vane remains free and overlapping the next adjacent vane whereby a portion of each vane may lift free of the next adjacent vane in a wind to permit venting of the umbrella top.

WIND-RESISTANT UMBRELLA

BACKGROUND OF THE INVENTION

1. Scope of Invention

This invention relates generally to table and beach umbrellas, and more particularly to an umbrella top formed of a plurality of separate elongated vanes or panels which are uniquely attached to one another to protect the umbrella top in wind.

2. Prior Art

Conventional table and beach umbrellas are susceptible to being upset and carried away, damaged or cause damage when strong gusts of wind are encountered. Various anchors, poles and other means of securing the elongated main umbrella pole are well known to at least partially deal with this problem. However, such anchoring means is quite dependent upon the surrounding support surface into which the anchor is positioned and may lead to damage to the main support pole itself.

Prior art teaches various attempts to provide a vented umbrella top to reduce the lifting forces and thus make them more wind resistant. However, most prior attempts do not effectively deal with the likelihood of the umbrella top becoming windborne, despite the fact that some of these attempts have become extremely complicated and inordinately heavy.

One successful attempt to answer this problem is disclosed in U.S. Pat. No. 3,386,455 invented by O'Rear which provides a wind-resistant umbrella which has been shown to be effective, relatively economically manufacturable, light weight and inexpensive. This invention, however, relies upon extreme flexibility of the individual vanes or panels and a somewhat complex support structure including a rigid periphery to support the vanes while still allowing them to flex and twist in wind.

The present invention represents an improvement over the O'Rear umbrella by eliminating many of the more heavy and cumbersome structural members and further improving the strength and configuration of each of the vanes.

BRIEF SUMMARY OF THE INVENTION

This invention is directed to a collapsible wind-resistant umbrella including an elongated main support pole and an umbrella top. The umbrella top includes a tubular secondary pole slidably translatable over the main support pole, a hub connected at an upper end thereof to the secondary pole and supportively engaged against a support member on the main support pole whereby the secondary pole and hub are supported on the upright main support pole. A plurality of vanes, each being wider at the outer end thereof, are pivotally connected in evenly spaced relation at a central or inner end thereof to and around substantially the entire hub periphery. A vane carrier is mounted for sliding translation over the secondary pole and a plurality of rigid or semi-rigid vane support rods are pivotally connected at one end thereof in evenly spaced relation to and around substantially the entire said vane carrier periphery. The end of each said vane support rod is pivotally connected to a mid point of one longitudinal edge of each corresponding vane. An elongated endless non-elastic cord extends circumferentially around, and is connected to each vane adjacent its outer or distal end. The other edge of each vane remains free and overlapping the next adjacent vane whereby a portion of each vane may lift free of the next adjacent vane in a wind to permit venting of the umbrella.

It is therefore an object of this invention to provide an improved wind-resistant collapsible umbrella with improved strength and simplified, lightened construction and manufacturing economy while remaining effective in reducing likelihood of wind damage.

In accordance with these and other objects which will become apparent hereinafter, the instant invention will now be described with reference to the accompanying drawings.

10 BRIEF DESCRIPTION OF THE DRAWINGS

FIG. 1A is a perspective view of the invention supported by an umbrella table, the umbrella top being in an open, in-use position.

15 FIG. 1B is a view similar to FIG. 1 with the umbrella top in a closed position.

FIG. 2 is another perspective view of the umbrella top in an open position.

20 FIG. 3 is an enlarged perspective view of the central portion of the umbrella top.

FIG. 4 is a perspective view of a vane or panel of the umbrella top.

25 FIG. 5 is a cross section view in the direction of arrows 5—5 in FIG. 4.

FIG. 6 is a view in the direction of arrows 6—6 in FIG. 2.

FIG. 7 is a partial section view in the direction of arrows 7—7 in FIG. 3.

30 FIG. 8 is a view in the direction of arrows 8—8 in FIG. 7.

FIG. 9 is a bottom view of a molded plastic clip for universally connecting each vane to the umbrella top hub.

FIG. 10 is a side elevation view of FIG. 9.

35 FIG. 11 is an exploded perspective view of the preferred support member for the umbrella top on the main support pole.

40 DETAILED DESCRIPTION OF THE INVENTION

Referring now to the drawings, the umbrella is there shown generally at numeral 10 and includes an umbrella top 12 and, in FIGS. 1A and 1B, is shown supported by its main support pole 20 within an aperture 22 of a table surface 24 and a lower support 26 of an umbrella table shown generally at numeral 14.

The umbrella top 12 includes a plurality of elongated vanes or panels 16 as best seen in FIGS. 4 and 5. Each of the vanes 16 is formed of thin sheet aluminum in the preferred embodiment, but molded plastic in other light somewhat flexible material may be utilized.

55 Each vane includes a flat central section, leading and trailing longitudinal margins 32 and 38 and an inner end 41, and an outer end 34 wider than the inner end 41. The leading longitudinal margin 32 includes a bead 30 formed along substantially the entire length thereof for added strength and stiffness and, it is believed by applicant to provide some aerodynamic benefit in wind. The trailing edge 38 is formed as a downwardly extending flange and doubled over for substantially greater strength and rigidity in this area of each vane 16.

60 The central or inner end 41 of each vane 16 includes an end notch 44 and a rectangular aperture 42 which facilitate connection of each vane to the hub 56 of the umbrella top 12, all of which is described herebelow in more detail. The distal

or outer end **34** of each vane is downturned so as to provide a shading periphery of the umbrella top **12** when in the open position. The very distal outer edge **36** is folded over for added rigidity and for presenting a smooth edge. An aperture **58** is provided in this outer end area of each vane **16** to receive a clip which is described more fully herebelow. A rubber attaching grommet **40** is positioned along a mid point of the flanged trailing edge **38** for connection to a vane-supported rod to also be described herebelow.

As best seen in FIGS. 3, 7 and 8, a central disc-shaped hub **56** is formed of two connected together aluminum plates **56A** and **56B** having a central aperture **86** formed therethrough. A tubular secondary pole **18** is connected to, and orthogonally extends downwardly from, this aperture **86**. This secondary pole **18** is substantially shorter in length than the main support pole **20** and is formed having a rectangular hollow cross section so as to loosely slidably engage over the main support pole **20**. A support member **84** in the form of a concentric snap ring is fitted into groove **88** circumferentially formed into main support pole **20** and also includes an annular friction-reducing thin flat ring **90** attached to the upper surface thereof which bears against and supports the lower surface of the hub **56** adjacent aperture **86**. By this arrangement, the downward weight of substantially the entire umbrella top **12** including the hub **56** and secondary pole **18**, is transferred to the ground through the table-supported main support pole **20**.

The circular outer peripheral margin **56C** of hub **56** includes a bead **78** formed into the lower panel **56B** and evenly spaced apart notches **80** formed entirely therearound. A molded plastic vane attaching clip **64**, best seen in FIGS. 9 and 10, includes a spherical ball **74** formed at one end thereof which is trapped within the bead **78** as best seen in FIGS. 7 and 8. Each notch **80** is widened at **82** so that the necked portion **76** of clip **64** will allow the clip **64** to pivotally moved downwardly in the direction of arrow C in FIG. 7, laterally back and forth in the direction of arrow D in FIG. 8 and about its longitudinal axis in limited fashion to reduce the stress and thus damage imposed upon each of the vanes **16** in wind as described more fully herebelow.

The clip **64** is snapingly connected to the vane **16** by forcibly engaging the large distal end portion **66** into the rectangular aperture **42** after notch **44** has been slidingly engaged beneath retaining tab **70** and against the end **68** of slot **67**. Notch **72** is sized in height to be just slightly greater than the thickness of the aluminum sheet used to form each vane **16** (about 0.03"). Tab **70** bears against the vane **16** to prevent excessive movement and rattling once clip **64** is secured in place.

Referring again to FIGS. 1A and 1B, FIG. 2 and FIG. 3, the umbrella top **12** also includes a vane carrier **46** which closely slidably engages concentrically over the rectangular shaped outer surface of the secondary pole **18**. This vane carrier **46** includes a locking member **50** which fixes the selected position of the vane carrier **46** after sliding movement in the direction of arrow E to a desired position along the length of the secondary pole **18**.

The vane carrier **46** also includes a circular flange **48** defining a perimeter having a plurality of closely and evenly spaced apertures formed therethrough. Each of these apertures is structured to retainingly receive one end **54** of an elongated vane support rod **52** preferably formed of slender aluminum stock material. This end **54** of each of the vane support rods **52** is connected into one of the apertures in the flange **48** of the vane carrier **46**. The other end **55** of each vane support rod **52** is pivotally connected through the grommet **40** to flange **38** of each vane **16**.

By this arrangement, as the vane carrier **46** is moved in the direction of arrow E in FIG. 3 along the secondary pole **18**, the umbrella top **12** is moved between the open and closed position shown in FIGS. 1A and 1B, respectively. All of the related components being pivotally connected one to another, the movement of the vanes **16** between these two positions is greatly enhanced and facilitated.

To further enhance an important preferred feature of the invention, and now referring to Figure 11, the rectangular sectioned tubular secondary pole **18** is preferably connected at its lower end concentrically to a molded plastic bearing or guide **100** which is preferably molded of nylon or other low surface friction material suitable for this application. The bearing **100** includes a cylindrical inner surface **102** which slidably engages over the main support pole **20** in closely aligned fashion. Upwardly extending corner bosses **104** securely and tightly engage within the corners of the secondary support pole **18** and are self-retaining and self-aligning in this manner.

A support collar **10**, also sized to snugly fit over the outer surface of the main support pole **20** shown in phantom, is positioned therealong and secured permanently to the main support pole **20** as by blind rivets **112** through apertures **114** or by other suitable means such as by peening or denting the mating surfaces or by threaded mechanical fasteners. A separate friction ring **108**, also formed of molded low-friction plastic, serves as a bearing between the lower ring-shaped surface **106** of bearing **100** and the upper surface of collar **110**. By this arrangement, all of the weight of the umbrella top **12** is placed against collar **110** and, thusly, upon the upright main support pole **20**.

The important preferred feature which the arrangement in FIG. 11 facilitates is the free rotation of the umbrella top **12** when in wind. As seen in FIG. 1A, when the wind is in the direction of arrow B, the leading edges of the respective vanes **16** lift into approximately the position there shown in phantom, which also induces a rotational force into the umbrella top **12**. Rotation of the entire umbrella top **12** in the appropriate direction of arrow A then occurs, the main support pole **20** remaining stationary. By allowing this free rotation of the umbrella top **12** in response to wind, in addition to the lifting motion of each of the vanes **16**, the likelihood of damage or upset of the umbrella top **12** is greatly reduced.

Lastly, the umbrella **10** may be provided with a decorative cap **28** which frictionally engages over the upper end of the main support pole **20**. Upon removal of this cap **28**, the umbrella top **12** may be lifted from the main support pole **20** for storage or cleaning.

While the instant invention has been shown and described herein in what are conceived to be the most practical and preferred embodiments, it is recognized that departures may be made therefrom within the scope of the invention, which is therefore not to be limited to the details disclosed herein, but is to be afforded the full scope of the claims so as to embrace any and all equivalent apparatus and articles.

What is claimed is:

1. A wind-resistant umbrella comprising:
an elongated main support pole;
a tubular secondary pole slidably translatable over said main support pole;
a hub having a periphery and connected at one end thereof to said secondary pole and supportively engaged against a support member on said main support pole whereby, when said main support pole is upright, said secondary pole and said hub are supported on said main support pole by said support member;

a plurality of vanes each having a central end, an outer end and trailing and leading longitudinal edges, said outer end being wider than said central end; each said central end pivotally connected in evenly spaced relation to and around substantially the entire said hub periphery; 5
 a vane carrier having a periphery and mounted for sliding translation over said secondary pole; a plurality of rigid or semi-rigid vane support rods each having a central end thereof pivotally connected in evenly spaced relation to and around substantially the entire said vane carrier periphery; 10
 an outer end of each said vane support rod pivotally connected along a mid point of said trailing longitudinal edge of each corresponding said vane; 15
 a clip attached adjacent each said vane outer end; an elongated substantially non-elastic cord extending circumferentially around and connected to each said clip; said leading longitudinal edge of each said vane remaining free and overlapping said trailing longitudinal edge of the next adjacent said vane, whereby a portion of each said vane may lift free of the next adjacent said vane and said umbrella top in a wind to permit venting of, and to prevent damage to, said umbrella. 20
 2. A wind-resistant umbrella as set forth in claim 1, wherein:
 each said vane includes a stiffening bead formed along the length of said leading longitudinal edge. 25
 3. A wind-resistant umbrella as set forth in claim 2, wherein:
 each said vane includes a downturned stiffening flange formed along the length of said trailing longitudinal edge. 30
 4. A wind-resistant umbrella as set forth in claim 3, wherein:
 each said outer end is downturned to produce an overhanging outer periphery on said umbrella. 35
 5. A wind-resistant umbrella as set forth in claim 4, wherein:
 each said central end is also universally connected to said hub periphery to facilitate vane axial rotation in wind. 40
 6. A wind-resistant umbrella comprising:
 an elongated main support pole;
 an umbrella top including:
 a tubular secondary pole slidably translatable and freely rotatable over said main support pole; 45
 a hub having a periphery and connected at one end thereof to said secondary pole;
 a support member on said main support pole supporting said hub and said secondary pole whereby, when said main support pole is upright, said secondary pole and said hub are supported at an upper end portion of said main support pole by said support member; 50
 a plurality of vanes each having a central end, an outer end and trailing and leading longitudinal edges, said outer end being wider than said central end; 55
 each said central end pivotally connected in evenly spaced relation to and around substantially the entire said hub periphery;
 a vane carrier having a periphery and mounted for sliding translation only over said secondary pole; 60
 a plurality of rigid or semi-rigid vane support rods each having a central end thereof pivotally connected in evenly spaced relation to and around substantially the entire said vane carrier periphery;
 an outer end of each said vane support rod pivotally connected along a mid point of said trailing longitudinal edge of each corresponding said vane; 65

a clip attached adjacent each said vane outer end; an elongated substantially non-elastic cord extending circumferentially around and connected to each said clip; said leading longitudinal edge of each said vane remaining free and overlapping said trailing longitudinal edge of the next adjacent said vane, whereby a portion of each said vane may lift free of the next adjacent said vane and said umbrella top in a wind to permit venting of, and to prevent damage to, said umbrella. 7. A wind-resistant umbrella as set forth in claim 6, wherein:
 each said vane includes a stiffening bead formed along the length of said leading longitudinal edge. 8. A wind-resistant umbrella as set forth in claim 7, wherein:
 each said vane includes a downturned stiffening flange formed along the length of said trailing longitudinal edge. 9. A wind-resistant umbrella as set forth in claim 8, wherein:
 each said outer end is downturned to produce an overhanging outer periphery on said umbrella top. 10. A wind-resistant umbrella as set forth in claim 9, wherein:
 each said central end is also universally connected to said hub periphery to facilitate vane axial rotation in wind. 11. A collapsible wind-resistant umbrella comprising:
 an elongated main support pole;
 a tubular secondary pole slidably translatable over said main support pole;
 a hub having a periphery and connected at one end thereof to said secondary pole;
 a support member connected to said main support pole supporting said hub and said secondary pole from downward movement whereby, when said main support pole is upright, said secondary pole and said hub are supported on said main support pole by said support member;
 a plurality of vanes each having a central end, an outer end and trailing and leading longitudinal edges, said outer end being wider than said central end;
 each said central end pivotally connected in evenly spaced relation to and around substantially the entire said hub periphery;
 a vane carrier having a periphery and mounted for sliding translation over said secondary pole between a closed and an open position;
 a plurality of rigid or semi-rigid vane support rods each having a central end thereof pivotally connected in evenly spaced relation to and around substantially the entire said vane carrier periphery;
 an outer end of each said vane support rod pivotally connected along a mid point of said trailing longitudinal edge of each corresponding said vane, a clip attached adjacent each said vane outer end; an elongated substantially non-elastic cord extending circumferentially around and connected to each said clip; said leading longitudinal edge of each said vane remaining free and overlapping said trailing longitudinal edge of the next adjacent said vane when said vane carrier is in said open position and said umbrella is also open, whereby a portion of each said vane may lift free of the

next adjacent said vane in a wind to permit venting of said umbrella.

12. A wind-resistant umbrella as set forth in claim **11**, wherein:

each said vane includes a stiffening bead formed along the ⁵ length of said leading longitudinal edge.

13. A wind-resistant umbrella as set forth in claim **12**, wherein:

each said vane includes a downturned stiffening flange ¹⁰ formed along the length of said trailing longitudinal edge.

14. A wind-resistant umbrella as set forth in claim **13**, wherein:

each said outer end is downturned to produce an overhanging outer periphery on said umbrella.

15. A wind-resistant umbrella as set forth in claim **14**, wherein:

each said central end is also universally connected to said hub periphery to facilitate vane axial rotation in wind.
